[57] ABSTRACT

A feed drive for a refuse compactor which has a mechanically driven compacting ram, and which includes a feed member for refuse that is driven between a loading and a feeding position in a refuse hopper by cam means actuated by movement of the ram.

DRIVE FOR REFUSE COMPACTOR

CROSS REFERENCE TO RELATED APPLICATION

This application is related to the disclosure of my co-pending application Ser. No. 151,814, filed June 10, 1971, for REFUSE COMPACTOR now U.S. Pat. No. 3,752,061.

BACKGROUND OF THE INVENTION

1. Field of the Invention.

This invention relates to feed mechanisms for REFUSE COMPACTOR.

2. Prior Art.

My previous application U.S. Ser. No. 151,814, filed June 10, 1971 now U.S. Pat. No. 3,752,061, shows a compactor of the general type illustrated in this application.

The jackscrew assembly shown therein works very well for a compacting member, and the feeding member has been improved to insure positive feeding of material to the jackscrew.

SUMMARY OF THE INVENTION

The present invention relates to improvements in refuse compactor feeders. The compactor feeder as shown herein is a cam operated device which operates from a cam block on the compactor member or plunger. The cam follower is mounted on a rock shaft or pivot shaft which has arms connected to move a slidably pusher feed member across the bottom of a storage hopper to push refuse to be compacted into a compacting chamber. After that, the jackscrew assembly is actuated to move the compactor member to compact the refuse, and when the jackscrew assembly approaches the end of its compaction stroke, the cam feed member is reset to its loading position by a separate cam. In this way the feed member in the hopper is positively reset in its loading position after each compacting cycle so that refuse that is being placed into the hopper will be positioned ahead of the feed member, and when the next cycle is started, a full charge of refuse will be introduced into the compaction chamber.

In addition, improvements in the drive ball nut for the jackscrew are provided for insuring that there will be no binding of the nut that drives the screw used in the jackscrew assembly for the compactor. Slight misalignments between the ram and the screw may occur because of normal tolerances or wear. The ball nut is mounted onto a separate spherical washer having a spherical seat, and is retained from rotation, but it can move a limited amount about its spherical seat to permit some misalignment between the threaded members.

BRIEF DESCRIPTION OF THE DRAWINGS

FIG. 1 is a side elevational view of the compactor in one stage of operation and with part of the outer wall broken away to reveal interior components;

FIG. 2 is a side elevational view of the compactor in another stage of operation with the outer wall broken away to reveal interior components;

FIG. 3 is a top plan view of the compactor as shown in FIG. 2;

FIG. 4 is a sectional view taken as on line 4-4 in FIG. 2 showing the detail of one support and drive link for a feed member;

FIG. 5 is a sectional view taken as on line 5-5 in FIG. 4;

FIG. 6 is a sectional view taken as on line 6-6 in FIG. 2 showing details of a cam member and friction torque limiting clutch that may be used for the feed drive;

10 FIG. 7 is a detailed side view of the cam and drive member;

FIG. 8 is a sectional view of the ball drive nut used with the jackscrew assembly, taken as on line 8-8 in FIG. 1; and

15 FIG. 9 is a sectional view taken as on line 9-9 in FIG. 8.

DESCRIPTION OF THE PREFERRED EMBODIMENT

20 The operation of the main portion of the compactor shown herein, and the controls, as well as the general concept of the compactor is all illustrated in my co-pending application Ser. No. 151,814, filed June 10, 1971, for REFUSE COMPACTOR. The description therein is incorporated herein by reference.

25 Referring now to FIGS. 1, 2 and 3, the compactor consists of a hopper module illustrated generally at 1 and a press module illustrated generally at 3. The hopper module 1 contains a hopper compartment 5 and a feed assembly consisting of a feed plate 7, a drive mechanism indicated generally at 9, and a feed deflector plate 35. The press module 3 contains a ram 11, a ram chamber 13, a drive motor and gear reducer 15, a jackscrew assembly designated generally by reference numeral 17 and a nozzle chamber 19. Refuse enters the compactor either through the door 21, or through a chute, (not shown), which is connected to the top of the hopper module 1 through doors that may be provided at the top of the compartment.

30 In the general explanation of the operation of the compactor, the refuse is deposited into the hopper compartment 5 of the hopper module 1. At this time the feed bar assembly 7 is retracted in its position as shown in FIG. 2, and the ram is in its lower position as shown also in FIG. 2. When sufficient refuse has accumulated in the hopper compartment 5, the ram 11 is raised to its upper position, as shown in FIG. 1, and the push bar assembly is driven forward or toward the ram chamber as will be explained, to urge the refuse into the ram chamber 13. Then, during the compaction cycle, the ram 11 is lowered to compact the refuse as the ram 11 travels through the ram chamber 13 and pushes the refuse through the nozzle chamber 19. This results in extrusion of the refuse through the nozzle chamber 19, which is designed to cause compaction of refuse in the ram chamber as the refuse is extruded.

35 Loose uncompacted refuse entering the hopper module 1 passes through a light beam from a photosensor indicated in dotted lines at 23. This photosensor can be wired in a convenient manner to control the motor and gear reducer 15. The refuse strikes the floor plate 24 of the hopper compartment 5, with the feed bar assembly 7 in its retracted position as shown in FIG. 2. As the refuse accumulates it gradually reaches the level of the photosensor 23. The photosensor 23 is provided with a time delay mechanism such as that it will close a switch to actuate the compaction cycle only when the

light beam is interrupted for more than a minimum of several seconds. For this reason, the passage of small batches of refuse through the light beam will not actuate the compaction cycle until a full load of refuse has accumulated in the hopper on the floor 24.

When a full load of refuse is accumulated in the hopper compartment 5, which is about even with the bottom of the deflection plate 35, photosensor 23 causes the motor and gear reducer 15 to be powered. At this point in the cycle the ram 11 and jackscrew assembly 17 are in their down position as shown in FIG. 2. The motor and gear reducer are connected through gearing to drive lead screw 25, which is mounted for rotation about its axis and held stationary in axial direction with respect to the motor and gear reducer on suitable supports. The lead screw drives a movable ball nut or follower nut 27, which is threaded on the screw 25. The follower nut 27 moves axially along the stationary lead screw 25 as the screw 25 is rotated. The follower nut 27 is connected to ram 11 by vertical supports 31. As shown, three vertical supports are used, for this connection, and are of the same construction as shown in my aforementioned application Ser. No. 151,814.

In its lowered position the ram 11 and supports 31 carry a ram shield plate illustrated at 43 in FIG. 3, to cover the opening between the hopper compartment and the ram chamber 13. The shield plate 43 is connected to supports 31 with brackets 43A.

When the motor and gear reducer 15 are first energized, they will drive the follower nut 27 and ram 11 upwardly along the lead screw 25 from the down position as shown in FIG. 2 to the up or loading position of the ram shown in FIG. 1. As the ram 11 is driven upward, the ram 11 passes through the ram chamber 13 and the ram shield 43 is raised to expose a passageway extending from the ram chamber to the hopper compartment 5. As a result, loose uncompacted refuse which is accumulated in the hopper compartment 5 in front of the feed bar 7 in its retracted position as shown in FIG. 2, is allowed to spill over from the hopper compartment 5 into the ram chamber 13 through the connecting opening passageway. When the ram 11 nears the top of its stroke, a cam block 32 attached to one of the supports 31 engages a cam follower assembly 33 comprising part of the feed bar assembly drive linkage. The cam follower assembly 33 will be more fully explained, but briefly the ram acts as a lever to drive a rock shaft 34 that is rotatably mounted in suitable bearings 37 to the compactor frame, in a suitable manner.

The rock shaft 34 extends across the unit, as shown in FIG. 3, and at opposite ends of the rock shaft, suitable drive arms 42 are located. These drive arms 42 are drivably connected to the rock shaft through hubs 42A, and as shown, the lower ends of the drive arms are attached through suitable rod end bearings to links 44 which in turn connect to a carriage 45 on each side of the feed bar assembly 7. The carriages 45 are shown in more detail in FIGS. 4 and 5. The links 44 are provided with spherical rod end bearings at their opposite ends which attach to the arms 42 and to the carriages 45 in the usual manner through the use of cap screws or the like.

When the cam block 32 strikes the cam follower lever 33, the cam follower drives through a friction clutch assembly to rotate the rock shaft 34 in a clockwise direction as viewed in FIG. 1, and this will move

the arms 42 simultaneously to pull the feed bar assembly 7 toward the ram chamber.

The deflector plate 35 mounted in the hopper compartment 5 deflects the refuse dropped into the door 21 ahead of the forward panel or face 6 of the feed bar assembly 7 when it is in its retracted position shown at FIG. 5. The feed bar assembly 7 comprises the leading panel 6, a flat top panel 10, and includes structural support members to which the carriages 45 are attached. The structural supports are shown only generally, and can be of any desired configuration to provide adequate strength for the feed bar assembly.

The feed bar assembly 7 is fitted into the hopper compartment with close clearances along the sides and bottom thereof with respect to the respective side walls 16 of the hopper compartment so that the refuse will not slip in between the feed bar assembly 7 and the side walls of the hopper compartment.

The feed bar assembly pushes the refuse from the hopper into the ram chamber 13 as the rock shaft is rotated by cam follower 33 which is actuated by cam block 32, and when the ram 11 and jackscrew assembly 17 reach the upper end of the stroke, the motor and gear reducer 15 are then stopped and reversed (the motor is reversible), which starts the downward stroke of the ram 11. The feed bar assembly 7 remains in its feed or forward position shown in FIG. 1 as the cam block 32 moves away from the cam follower 33. The ram and jackscrew continue the downward movement and the ram plate 43 closes the passageway between the ram chamber and the hopper compartment as the ram lowers. The ram moves downwardly through the ram chamber to drive the refuse in the ram chamber ahead of it, pushing and compacting the refuse into the nozzle chamber 19 which is reduced in cross sectional area, resulting in the extrusion of the refuse through the nozzle chamber 19. The ram 11 passes completely through the ram chamber 13 to completely clear the ram chamber of refuse.

Suitable shearing bars, which are not shown, can be provided with the ram to shear off any refuse material across the opening between the hopper compartment 5 and the ram chamber 13. In the lower portions of the stroke of the ram 11, a second cam block 50, which is attached to the same support 31 as the cam block 32, engages the upper portion of the cam follower 33, and through the friction clutch assembly, which will be more fully explained, the cam follower rotates the rock shaft 34 in opposite direction from the previous movement, and moves the arms 42 back toward their original retracted position as shown in FIG. 2 with the feed bar assembly 7 retracted. The links 44 are sufficiently strong to carry compression loading of the empty feed bar assembly as it is moved back to its retracted position. The last few inches of travel of the ram resets the feed bar assembly so that the hopper compartment is open and ready to receive additional refuse. The ram stays in its down position, as shown in FIG. 2, until the hopper compartment is again filled so that the photosensor 23 starts the motor and gear drive 15 to again repeat the compaction cycle previously described.

It should be noted that the feed bar assembly pre-compresses the refuse as it moves the refuse into the ram chamber, to aid in the overall compression of the refuse. The nozzle 19 can lead to suitable bagging apparatus or attachments, or the compacted refuse can be disposed of in any other desired way.

It should also be noted that the entire electrical circuit shown in my previous application Ser. No. 151,180 can be incorporated into this unit for operation, and therefore the controls here are not shown in any detail. Even manual operation of the motor and gear reducer can be effected, if desired.

Now referring to FIG. 4, a typical carriage support 45 for the feed bar assembly 7 is shown. There is one of these carriage supports, operating on an associated track, on each side of the hopper compartment, and each of the carriage supports 45 is controlled by one of the arms 42. As shown, the feed bar assembly face panel 6 is illustrated fragmentarily, and the side wall 16 has a slot-like opening 16A defined therein. The carriage 45 is fixed to the support members for the feed bar assembly 7, and includes an outwardly extending support 51 that extends through the slot 16A, and to which the respective link 44 is attached through the typical spherical rod end bearing.

The support 51 has a downwardly depending plate member 52 attached thereto, and this member 52 is positioned on the outside of the wall 16. The member 52 carries a pair of rollers 53, which are rotatably mounted on the inner side of the support 52 and which rotatably engage a flange 54 of a track member 55 which is attached to the side wall 16 of the hopper compartment and extends along the path of the feed bar. The flanges 54 are generally parallel to the bottom wall 24 of the hopper compartment. The track member 55 thus provides the support and guide means for the feed bar assembly 7 as the arms 42 are actuated to pull the feed bar assembly 7 to its feeding or forward position, and also to push the feed bar assembly back to its retracted position. In addition, the support 52 has a pair of side guide rollers 56 mounted thereon. These side guide rollers are rotatably mounted about vertical axes, and engage the track 55 on the outer surface thereof, which is parallel to the surface of the wall 16. This keeps the feed bar from moving sideways in the hopper compartment to a point where it would hang up or rub against the opposite side walls of the hopper compartment. The carriages provide a stable adequate guide for movement of the feed bar as the feed bar is actuated.

Now, referring to FIGS. 6 and 7, details of a typical cam follower lever is shown with a friction clutch for driving the rock shaft to insure that overloads do not occur through the drive member. However, in many instances the friction clutch is not necessary, but a fixed connector, such as a key or drive pin between the cam follower and the rock shaft is all that is needed.

As shown, the cam follower 33 is a flat lever member that is driven through the friction clutch assembly illustrated generally at 60 to the rock shaft 34. The rock shaft 34 mounts a hub 61 that is drivably mounted to the rock shaft with a suitable pin or in other ways. The hub includes a backing plate 62, against which a first friction disc 63 is fitted. The cam follower 33 has an opening that slips over the central portion of the hub 61, against the first friction disc 63, and a second friction disc 63 is then placed on the outer surface of the cam follower 33. A backing plate 64 is provided, and is spring loaded through a bellville spring 65 and a nut 66 that is threadably mounted on the outer end of the hub that protrudes beyond the backing plate 64. The arm 42 is connected to the rock shaft with a suitable drive pin or the like.

The cam follower lever 33 itself is made so the end which is engaged by the cam blocks is offset to provide alignment with the cam blocks attached to the supports 31. The cam follower 33 has a laterally extending member 33A that in turn rotatably mounts a cam follower 33B that is positioned in vertical alignment with the cam blocks 32 and 50 so that the blocks will engage the roller 33B to actuate the cam follower and the rock shaft 34 during the stroke of the cam.

In FIGS. 8 and 9, details of the seat for the ball nut used with the lead screw 25 are shown. The supports 31 for the ram are attached to portions of a base 67 that is connected to the supports 31 and this base 67 in turn supports a ball nut housing that can be formed in any desired manner, but includes a wall 68 that surrounds the ball nut, and an overlying flange 69 that is removably attached to the wall 68, but which holds the nut captive in the housing when the nut is in place. The base 67 has an opening through which the lead screw 25 extends, and a typical ball nut 27 is provided for threadably receiving the screw 25. The nut 27 has a flange at the lower end thereof. This flange comprises an annular member extending outwardly from the nut and is indicated at 70. The flange 70 has a pair of slots 71 defined therein diametrically opposed from each other, and adapted to mate with lugs 72 that are attached to the housing wall 68. These lugs 72 are thus fixed with respect to the ball nut housing, and with respect to the ram and ram supports 31. The interlocking lugs 72 and grooves 71 on the ball nut provide for some movement of the nut with respect to the housing, but the lugs 72 prevent the nut 27 from rotating with the lead screw when the screw 25 is rotated by the motor and gear reducer.

In order to permit the nut to cant slightly if the lead screw is misaligned with respect to the ram, and with respect to the supports 31, a spherical seat (concave) washer 73 is placed inside the housing wall 68, and on top of the base 67. The ball nut flange 70 is provided with a spherical lower surface 74 (convex) that mates with the concave surface of the washer 73, so that there can be some movement of the ball nut flange itself with respect to the washer 73, as constrained by the lug 72 and the slot 71. This permits the ball nut to cant slightly in different directions due to slight misalignment between the ram and ram supports 31 and the screw 25. The nut will be supported and still free to move so that there won't be any binding between the nut and the screw 25. The nut will still be prevented from rotating so that as the screw 25 is rotated, the ram will be moved up and down along the screw for the compaction cycle. The housing for the washer 73 can be packed with grease for adequate lubrication.

The compactor thus includes improvements in the feed mechanism and ball nut support for increased reliability and positive feed.

What is claimed is:

1. In a refuse compactor having a compacting member and a compaction chamber, and power means for moving such compacting member in a compacting stroke from a loading position to a compacting position, a hopper positioned adjacent said compaction chamber for receiving refuse to be compacted, said hopper communicating with said compaction chamber, a feed bar assembly within said hopper to foreceably move refuse in the hopper into the compaction chamber, said feed bar assembly being moved between a re-

tracted loading position and a feeding position, a linkage connected to said feed bar, and a cam follower, means to drivably connect said cam follower to said linkage, and a cam member mounted on said compacting member to mechanically engage said cam follower in at least in portions of said compacting stroke to selectively move said feed bar between said feeding and retracted positions during preselected portions of said compacting stroke.

2. The combinations specified in claim 1 wherein said cam follower comprises a lever member, and said means to drivably connect said cam follower to said linkage comprises a rock shaft, means drivably connecting said lever member and said rock shaft, said rock shaft being rotatably mounted on said compactor, and arm means drivably mounted on said rock shaft and connected to said linkage for moving said linkage as said rock shaft rotates.

3. The combination as specified in claim 1 wherein said cam follower comprises a lever member, and said means connecting said cam follower to said linkage comprises friction clutch means to permit slipping of said lever member when the force exerted thereon exceeds a preselected amount.

4. The combination as specified in claim 1 where said compacting member comprises a ram, a screw for driving said ram, a drive motor for rotating said screw, and a nut mounted on said screw and coupled to said ram, and mating spherical seat means between said nut and said ram to permit limited movement of said nut relative to said ram resulting from misalignment between said screw and said nut.

5. The combination as specified in claim 4 wherein said nut is connected to said ram by slotted linkage means permitting a limited amount of movement of said nut on said spherical seat means while preventing

rotation thereof with said screw.

6. A refuse compactor comprising a housing having a ram chamber, a ram mounted for movement in said chamber between a loading and a compacting position during a ram stroke, power means for driving said ram, a hopper positioned adjacent said ram chamber and communicating therewith through a provided opening, said hopper including a feed member movable between a retracted position wherein said hopper receives gravity fed loose refuse and a feeding position wherein refuse in said hopper is moved into said ram chamber, and a cam drive assembly for moving said feed member between the retracted and feeding positions, said cam drive assembly comprising a cam follower, means to drivably connect said cam follower to said feed member, and a cam member mounted directly on said ram and engaging and driving said cam follower at least in portions of said stroke to thereby move said feed member between its respective positions.

7. The combination as specified in claim 6 wherein said cam member comprises a pair of blocks mounted on said ram and positioned to engage said cam follower adjacent the opposite ends of said ram stroke.

8. The combination as specified in claim 6 wherein said means to drivably connect comprises a rock shaft mounting said cam follower, arm means mounted on said rock shaft on opposite sides of said hopper, link means extending from said arm means to said feed member, whereby pivotal movement of said rock shaft caused by movement of said cam follower causes said arms to move said feed member.

9. The combination as specified in claim 8 and torque limiting means between said cam follower and said rock shaft to limit the amount of torque carried by said rock shaft.
